CLAIM

The ornamental design for a removable cargo shelf assembly for a vehicle, as shown and described.

DESCRIPTION

FIG. 1 is a perspective view of a top removable cargo shelf assembly for a vehicle showing my new design;

FIG. 2 is a front elevation view thereof;

FIG. 3 is a back elevation view thereof;

FIG. 4 is a bottom view thereof;

FIG. 5 is a left side elevation view thereof;

FIG. 6 is a right side elevation view thereof;

FIG. 7 is an enlarged perspective view thereof, with the platform shown folded and partially broken away for clarity of illustration. The broken lines showing of the seat back of a vehicle is for illustrative purposes only and forms no part of the claimed design;

FIG. 8 is an enlarged top perspective view of the frame of the removable cargo shelf assembly for a vehicle in partially folded condition and shown separately for clarity of illustration; and,

FIG. 9 is an enlarged fragmentary bottom perspective view of the platform and a portion of the frame thereof.
